UNITED STATES PATENT OFFICE.

JOHN HERGESHEIMER, OF GLENSIDE, PENNSYLVANIA.

CALL SYSTEM.

1,093,132.

Specification of Letters Patent.

Patented Apr. 14, 1914.

Application filed March 5, 1913. Serial No. 752,007.

To all whom it may concern:

Be it known that I, JOHN HERGESHEIMER, a citizen of the United States, and a resident of Glenside, in the county of Montgomery 5 and State of Pennsylvania, have invented a certain new and useful Call System, of which the following is a specification.

The principal object of the present invention is to provide simple, comparatively inexpensive and reliable means for indicating from a central station at various points throughout a factory or place of business, to which various employees may go, that a certain one of such employees is wanted 10 either at some central point or at a telephone communicating with that point.

Another object of the present invention is to provide for the accomplishment of the above object in a quiet, yet certain manner. 20 The invention will be claimed at the end hereof, but will be first described in connection with the embodiments of it chosen from other embodiments for the sake of illustration.

25 In the drawings, Figure 1 is a diagrammatic view illustrating a call system embodying features of the invention and showing the call station and one sub-station. Fig. 2, is a view illustrating a detail of construction. Fig. 3, is a view illustrating a modification, and Fig. 4, is a front view of the call station.

Referring to Fig. 1, 1 is a plug contact board which may be faced with insulating 35 material 2, so as to prevent making contact until the plug 3 is properly inserted into one of the holes 4. Each hole 4 corresponds with the name or number of the person to be summoned and in order to call a certain person the plug is inserted into the proper hole. 40 5, is a solenoid or winding and the movable core 6, thereof is provided with a contact finger 7 that traveling over the contact points 8 makes and breaks contact. The core 6 is also provided with a stop 9 adapted to collide with the contact pin 3 and thus arrest the travel of the solenoid. As shown the stop 9 is mounted on a post 10. 11 is a valve consisting of a disk with holes in it 45 and which is afforded a slight range of motion in respect to the screw by which it is connected with the core 6. The top of the solenoid is closed as at 12 and the core 6 is grooved as at 13. In consequence of this 50 construction air may escape from the center

of the coil slowly when the core is rising so that the core rises slowly but in descending the valve and groove permit the air to escape rapidly so that the core may drop quickly. The purpose of this arrangement is to cause 60 the makes and breaks at the parts 7 and 8 to occur at comparatively long intervals. It may be said that the number of contacts 8 corresponds with the number of holes 4.

There may be many sub-stations and since 65 they are all duplicates and are electrically connected in multiple it follows that a description of one is sufficient.

At the sub-station there is a dial 14 upon which appear the names of the various persons, any one of which may be summoned from the call station. There is also at the sub-station a hand or pointer 15 which by pointing to a certain name indicates the person wanted. This hand is operated in one 70 direction by a ratchet wheel 16 and in the other direction by gravity.

17, is a spring actuated detent for preventing undesirable movement of the ratchet wheel.

18, is a driving pawl actuated by a spring 80 19 and retracted by the armature lever 20 and electro-magnet 21.

If desired the armature lever 20 may be provided with a striker 22 which co-operates 85 with a bell 23.

There is a source of current as 24. Current passes by 25, plug 3, board 1 and thence it divides, one part passing by 26 through the coil 5 and by 27 back to the source 24. 90 Another part passes by 28 through the core 6 or plunger 6 and thence by the contacts 7 and 8 intermittently by the conductor 29 through the magnet 21 and by the conductors 30 and 31 back to the source. Another 95 part passes by the conductor 32 through the coil of the magnet 33 and thence by the conductor 34 to the conductor 31 back to the source. The effect of these various currents is that the magnet 33 mounted on the spindle 35 of the ratchet wheel 16 is energized and attracting the pointer 15 makes it in effect one piece with the ratchet wheel. Plunger 6 rises slowly and in so doing makes and breaks the circuit through the magnet 105 21 with a suitable interval between each make and break. At each make the pawl 18 is drawn forward to engage a tooth of the ratchet wheel and at each break the spring 19 advances the ratchet wheel one 110

tooth. In consequence of all this the ratchet wheel is advanced tooth by tooth until the stop 9 hits the end of the pin 3, when the ratchet wheel and the pointer 15 come to rest and remain at rest opposite the name on the dial that corresponds with the name that appertains to the hole in which the plug is inserted.

If desired electric lamps, as 36 and 37, 10 may be placed across the circuits of the magnets 21 and 33, the former will flash and the latter will burn steadily. Instead of lamps and bells other signal devices may be employed.

15 As soon as the plug 3 is pulled out all of the circuits are interrupted, the magnet 33 is demagnetized and the pointer drops back to its initial position ready for another call. Instead of connecting the pointer with the 20 ratchet wheel 16 by means of an electro-magnet in order to permit the pointer 15 to drop back, the ratchet wheel may be fast to the pointer and the pointer and ratchet wheel may be permitted to drop back together. This may be accomplished as shown 25 in Fig. 3, in which the electro-magnet 38 operates when energized to draw the detent 11 and pawl 18 out of mesh. This magnet 38 is in a circuit that can be made and broken 30 by a switch, diagrammatically shown at 39 in Fig. 3. The switch 39 serves to make and break the circuit 40 from the source 24 through the magnet 38. This switch will be opened during the call and will be closed 35 after the call is answered so as to permit the pointer and ratchet wheel to return to starting position.

The number of names that may be used 40 is practically unlimited. Upon one board 1, the holes 4 may be staggered and in that way a number of names can be accommodated, but the number of boards may be increased.

45 As shown in Fig. 4, three boards 1, 1^a and 1^b are shown and they are interconnected as is diagrammatically shown by the conductors 41 and 42. The core 6 of each board is provided with a contact 43 that they may make contact with conductors 44 and 45, leading to the other end of the next coil in 50 the series. One end of all of the coils 5 is connected by branches 27^a and 27^b and conductor 27 with the side of the source opposite to the side to which the plug 3 is connected by the conductor 25 and the other end 55 of each of the coils, except the coil 5, is normally disconnected and is dead until it is brought into circuit by a contact 43 and one of the conductors 44 and 45. All of the contacts 8 are connected to a common conduct- 60 ing plate 46 with which the wire 29, Fig. 1, is connected.

Having reference to Fig. 4, if the plug be inserted, for example, as shown, current is 65 established in the manner described in con-

nection with Fig. 1, through the coil 5 of board 1 and through the various circuits described in that figure so that the core 6 of board 1 rises to its full height making its full number of makes and breaks at the contact 7 and 8 and when it reaches its full height current is established by the contact 43 through the conductor 44 so that the coil of the next board 1^a is energized and its core rises causing additional makes and breaks at the contacts 7 and 8 until the further rise of this core is interrupted by the pin 3 contacting with the stop 9.

70 From this description it is believed that the operation of the plurality of boards will be understood, although it may be said that the circuit for the coil of the board 1^a is from the plug 3 through the interconnected boards through the plunger of the board 1, the contact 43, the conductor 44, the coil of the board 1^a by 27^a and 27 back to the battery or course.

75 It will be obvious to those skilled in the art to which the invention relates that modifications may be made in details without departing from the spirit of the invention and hence I do not limit myself in regard to those matters, nor further than the prior state of the art may require, but

80 Having thus described the nature and objects of my invention, what I claim is new and desire to secure by Letters Patent is—

85 1. A call system comprising a freely movable pointer and its complemental plate or face, an electro-magnetic annunciator mechanism having a rotating element with which the pointer may be connected and disconnected, a make and break device and its circuit for actuating said annunciator mechanism with a step by step movement, a solenoid having a circuit and provided with a core for operating the make and break device, an electro-magnet and its circuit for connecting and disconnecting the pointer and 90 said rotating element, and switch mechanism 95 for controlling said circuits and including means for mechanically arresting the core of the solenoid at the end of its travel to position the pointer at the end of its travel, substantially as described.

100 2. A call system comprising a freely movable pointer and its complemental plate or face, an electro-magnetic annunciator mechanism having a rotating element with which the pointer may be connected and disconnected, a make and break device and its circuit for actuating said mechanism with a 105 step by step movement, a solenoid having a circuit and provided with a core for operating the make and break device, means for retarding the movement of said core when 110 its coil is energized to insure step by step motion of said mechanism, an electro-magnet and its circuit for connecting and disconnecting the pointer and said rotating ele- 115

120 125 130

ment, and switch mechanism for controlling said circuits and including means for mechanically arresting the core of the solenoid at the end of its travel to position the pointer at the end of its travel, substantially as described.

3. A call system comprising the combination of a ratchet wheel, a freely movable pointer and its plate or face, spring pawl-
10 and-ratchet connections for driving the ratchet wheel, an electro-magnet and its circuit for operating said connections, a series of contacts and their contact maker for making and braking the circuit of said electro-
15 magnet, a solenoid and its core for operating the contact maker, a second electro-magnet and its circuit for connecting and disconnecting the pointer and ratchet wheel, a plug board, and a plug for establishing and dis-
20 establishing said circuits and for mechanically limiting the travel of the solenoid after it has operated to shift the pointer into position corresponding with the plug.
4. In a call system the combination of a
25 step-by-step annunciator mechanism and a step-by-step transmitting mechanism and their circuits, a self-setting pointer freely movable in respect to the annunciator mechanism, and electro-magnetic connections for connecting said pointer with said annunciator mechanism to drive the pointer and for disconnecting the pointer and annun-
30

ciator mechanism to permit the pointer to reset itself.

5. In a call system the combination of a 35 solenoid coil, a circuit interrupter, a solenoid core for operating the interrupter, a plug board, a plug for closing the solenoid circuit, and provisions whereby the plug mechanically arrests the travel of the core, 40 substantially as described.

6. In a call system the combination of a solenoid coil closed at one end, a circuit interrupter comprising a line of contacts, a solenoid core provided with a contact adapt-
45 ed to travel over the first mentioned contacts, and an air valve and its complemental vent for limiting the rate of travel of the core under the influence of the coil, substantially as described.

7. The combination in a call system of a transmitter and a step-by-step receiving mechanism including a pointer, of an electro-magnet for coupling the pointer with the receiving mechanism and for uncoupling the pointer to permit it to return to starting position, and a plug for mechanically arresting the transmitter and for electrically coupling and uncoupling the pointer.
